UNITED STATES PATENT OFFICE.

SIMON REINSBERG, OF QUINCY, ILLINOIS.

MACHINE FOR MAKING BUTTONS.

No. 917,487.

Specification of Letters Patent.

Patented April 6, 1909.

Application filed September 9, 1905. Serial No. 277,754.

To all whom it may concern:

Be it known that I, SIMON REINSBERG, a citizen of the United States, residing in Quincy, in the county of Adams and State of Illinois, have invented certain new and useful Improvements in Machines for Making Buttons, of which the following is a full, clear, and exact description, reference being had to the accompanying drawings, forming 10 part of this specification.

My invention relates to a machine for use in manufacturing pearl or other buttons and including therein means for milling the button blanks and drilling the eye-holes therein.

15 Figure I is a front elevation of my machine. Fig. II is a side elevation of the machine. Fig. III is a top or plan view of the machine. Fig. IV is a horizontal section taken on line IV—IV, Fig. I with the parts beneath said 20 line shown in plan view. Fig. V is a horizontal section taken on line V—V, Fig. I with the parts beneath said line shown in plan view. Fig. VI is a horizontal section taken on line VI—VI, Fig. I, with the parts 25 beneath said line shown in plan view. Fig. VII is an enlarged plan view of a chuck table of the machine, the cam track adjacent to said table and one of the cutters, and also showing in cross section the stems of the drill 30 chucks. Fig. VIII is a vertical cross section taken on line VIII—VIII, Fig. VII. Fig. IX is a view partly in elevation and partly in vertical section of one of the chucks, the mechanism by which it is controlled and 35 means for removing the finished button from the chuck. Fig. X is an elevation of a modification of the means for milling the button blanks. Fig. XI is a top or plan view of the extra milling attachment shown in Fig. X.

40 1 designates the main frame of my machine and 2 is an immovable column surmounting said frame and around which various parts of the mechanism of my machine operate. This column also serves as a support for 45 other members of the machine.

45 3 designates a head frame that is clamped to the column 2 near its upper end and 4 is a hanger arm, see Fig. I, secured to and depending from the head frame 3. In this 50 hanger arm is journaled a shaft 5 that is adapted to carry a milling wheel 6, the said shaft being provided with a pulley 7 to which power may be applied for the purpose of imparting rotation to the shaft.

55 8 is a hanger arm secured to and depending

from the head frame 3. In this last named hanger arm are journaled the shafts 9 of drill chucks 10, each of which is designed to hold a drill *a* utilized in boring the eye-holes in the button blanks. 60

11 are spring stripper fingers suitably supported by the hanger arm 8 and straddling the drills for the purpose of stripping the button blanks therefrom after the drill has passed through them and is being withdrawn 65 in the manner to be hereinafter described.

The shafts 9 of the drill chucks are equipped with pulleys 12 to which belts may be applied for the purpose of rotating the drill 70 chucks.

13 designates a hanger arm secured to and depending from the head frame 3, see Fig. II. In this hanger arm is journaled the shaft 14 that is designed to carry a suitable reaming tool by which the button blanks 75 may be concaved. The shaft 14 is equipped with a pulley 15 adapted to receive a power belt.

16 designates a main drive shaft that is journaled in a standard 17, see Fig. II, and 80 from which power is conveyed to the shafts of the milling, drilling and reaming tools previously mentioned.

18 designates a chuck table rotatably fitted to the column 2 so as to revolve there-around. This chuck table is provided with 85 a series of apertures 19 extending vertically therethrough and arranged in a circular course.

20 designates a turn table located beneath 90 the chuck table 18 and loosely surrounding the column 2 so that said turn table and chuck table may revolve around said column with uniformity. The turn table has a hub 21 that extends above the main plane of the 95 table and serves as a rest for the chuck table and also extends beneath the main plane of the table to provide for the application of means by which the chuck and turn tables are rotated, and also for the vertical reciprocation of the turn table by means to be hereinafter described. In the turn table 20 and in vertical alinement with the apertures 19 in the chuck table are apertures 22, see 100 Fig. VIII.

23 designates a series of split chucks by which the button blanks *b* are designed to be held. The chucks 23 may be of any desirable number according to the number 105 of tools that are to be used in operating upon 110

the button blanks and so that two chucks will be susceptible of being brought to positions away from the tools at times and be opened to permit of the introduction of a button blank and the removal of a finished button on which the tools have operated. The shanks of the chucks are of less diameter than the apertures 19 in the chuck table and are centrally located in said apertures 5. 10 while the lower ends of the shanks are seated in the apertures 22 in the turn table 20 to be carried thereby, the said shanks being preferably held in the last named apertures by nuts 24 applied to their lower ends. Each of 15 the chucks is provided with a recessed seat 25 in which the button blank is held and the shank of each chuck is provided with a longitudinal bore. 20 are ejector rods located in the longitudinal bores of the chuck shanks and adapted to reciprocate therein for the purpose of lifting the buttons from the seats in the chucks after they have been finished. These ejector rods are actuated in a manner to be subsequently explained. 25

27 designates sleeves fitted in the apertures 19 in the chuck table and surrounding the shanks of the chucks 23. The sleeves are preferably conically formed interiorly, 30 both at their upper and lower ends to provide both for proper bearing for the upper ends of the sleeves against the tapering heads of the chucks and lateral play of the sleeves. At the lower end of each sleeve is an annular 35 flange 28.

29 are lift springs that surround the chuck shanks and which rest upon the turn table 20 and bear against the lower ends of the sleeves 27. These springs serve to normally 40 hold the sleeves in elevated positions so that they will engage the heads of the chucks to hold them in closed condition.

30 designates retracting yokes surrounding the sleeves 27 and having internal flanges 31 45 that are adapted to impinge against the annular flanges 28 of said sleeves. At the inner ends of the retracting yokes are pivot studs 32 that rest in the recesses 18' in the perimeter of the hub of the chuck table 18. 50 At the outer ends of the retracting yokes are rollers 33 adapted to be engaged by a member to be hereinafter mentioned and through the medium of which said yokes are tilted in a downward direction to retract the sleeves 55 27 and permit the chucks to open.

34 designates a lifting table loosely surrounding the hub 21 of the turn table 20 so as to be unaffected by rotation of said table. This lifting table is susceptible of vertical 60 movement and it is directed in such movement by guide posts 35 surmounting the main frame of the machine, see Figs. I, II, IV and V. The posts 35 also serve to prevent rotation of said lifting table. 65 36 designates a pair of upright arms car-

ried by the lifting table 34. To the upper ends of these arms is attached a cam track 37 which is located adjacent to the perimeter of the chuck table 18 and is in the path of travel of the rollers 33 carried by the retracting yokes 30. During the rotation of the turn table 20 and chuck table 18 of the machine the rollers 33 pass beneath the cam track 37 when the chucks that are not passing beneath the tools of the machine are brought into positions to be opened and held in open position for the extraction of the finished buttons and the introduction of blanks to be operated upon. As each chuck containing a finished button is moved into proximity with one end of the cam track the roller 33 of the retracting yoke corresponding to such chuck passes beneath the cam track, thereby causing the yoke to be tilted downwardly with a result of retracting the corresponding sleeve 85 27 and permitting the chuck to open for the extraction of the button. This chuck is then advanced and the next adjacent retracting yoke roller passes beneath the cam track to cause depression of the retracting yoke by 90 which it is carried so that the button may be in turn extracted therefrom when the chuck opens. The chuck first opened at this time remains in open condition, due to the corresponding spreader yoke being still depressed 95 by the cam track, and said chuck is in condition for the introduction of the button blank to be subsequently operated upon by the tools of the machine after the chuck has been closed when the turn table and chuck table 100 are rotated another step to separate the first named retracting yoke from the cam track.

38 designates a finger wheel that is carried by the hub of the turn table 20 and which is adapted to be actuated to impart an intermittent or step by step rotation to the turn table and chuck table of the machine. 105

39 designates a vertical driven shaft that is journaled in the lifting table 34 and has its lower end stepped into the main frame of the 110 machine.

40 is a trip arm fixed to the shaft 39. This trip arm is provided with a roller 41 that is adapted to be carried into engagement with the fingers of the wheel 38 to impart intermittent rotation thereto and rotate the turn table and chuck table upon each complete rotation of the driven shaft 39. The shaft 39 has fixed thereto a worm wheel 42, see Figs. I, II and VI. 115

43 is a horizontal shaft with a pulley 44 to which power is communicated from the main drive shaft 16. On the shaft 43 is a worm 45 that meshes with the worm wheel 42 to impart rotation to the vertical driven shaft 39. 120

46 is a cam fixed to the driven shaft 39. 47 designates a bracket mounted upon the main frame of the machine and provided with an opening 48, see Fig. II. This bracket has fitted to it an adjustment plate 130

49, see Fig. I, that has slot and screw connection with the bracket at 50 and is provided with an opening 51 adapted to register with the opening in the bracket. This adjustment plate is held in adjusted position by a set screw 52 passing through the bracket at its lower end and bearing against the lower end of the adjustment plate.

53 designates a lifting yoke that surrounds 10 the column 2 adjacent to its lower end and is provided with an arm 54 which rests in the opening 48 of the bracket 47 and in the opening 51 of the adjustment plate 49, the said arm being adapted to be adjusted vertically 15 by said adjustment plate. The lifting yoke is provided at its end opposite that bearing the arm 54 with a stem 55 that carries a roller 56 which rides upon the cam 46 carried by the driven shaft 39 and through the medium of which said yoke is moved vertically. Within the lifting yoke is a collar 57 that is loosely fitted to the column 2 to reciprocate 20 vertically thereon beneath the hub 21 of the turn table 20 in order that when said collar 25 is reciprocated it will impart vertical movement to the turn table and the parts carried by it. The lifting yoke 53 is connected to the collar 57 by screws or pins 58 passing through the sides of the yoke and seated in 30 said collar. It will be seen that when the driven shaft 39 is rotated the cam 46 will travel beneath the lifting yoke roller 56 and by raising said yoke impart the desired vertical motion to the collar 57.

35 59 designates a cam fixed to the driven shaft 39 adjacent to its upper end.

60 is a locking bolt that is reciprocally positioned in a guide block 61 supported by an extension arm 34' projecting from the 40 lifting table 34. This locking bolt is adapted to enter either of a series of notches 20' in the turn table 20 for the purpose of holding said turn table from rotation when it is brought to the proper position for one or 45 more of the button finishing tools to operate upon a button blank carried by the chuck 10 beneath the tool. The locking bolt is surrounded by an expansion spring 62 that tends to force the bolt inwardly toward the 50 turn table to enter one of the notches therein.

63 is a retracting bell crank lever pivoted at 64 to the lifting table extension arm. One arm of this lever is fitted to the locking bolt 60 and the other arm is provided with a 55 roller 65 that is adapted to be engaged by the cam 59, whereby upon the rotation of the driven shaft 39 the cam 59 carried thereby will strike against said roller and act to rock the retracting lever for the purpose of 60 withdrawing the locking bolt from the notch in the turn table in which it was previously seated. The turn table is thereby freed to partake of its next intermittent movement which is continued until the next adjacent

notch in the turn table is brought into a 65 position to receive the locking bolt.

34^a, see Figs. I, II and IX, designates a cam surmounting the lifting table 34 in a position immediately beneath that to which each chuck 23 of the machine is brought at 70 the time the chuck is to be opened as previously described, and the finished button is to be discharged therefrom. This cam is adapted to be engaged by the ejector rods 26 passing longitudinally through the shanks of 75 the chucks and as the ejector rod in the chuck from which the finished button is to be discharged is brought to said cam, it rides thereonto and is moved vertically to lift the button from the open chuck as seen in Fig. 80 IX. When the buttons are released from the chucks they may be conveyed from the machine by any suitable means such as a suction pipe 66 shown in Fig. IX.

In Figs. X and XI I have shown a modification in which the head frame 3 of the machine carries in addition to the hanger arm 4 and the milling wheel 6 and its shaft, a second hanger arm 4' in which is journaled a shaft 5'. This shaft is equipped with a 90 beveled pinion 5^a that meshes with a beveled pinion 5^b fixed to a shaft 5^c extending at right angles to the shaft 5'. The shaft 5^c is adapted to have applied to it a milling wheel 6' which is positioned at right angles to the 95 milling wheel 6 and which is adapted to operate upon the button blanks to produce a cross-cut groove therein extending at right angles to the grooves produced by the milling wheel 6. The buttons being produced, may 100 thereby be made with crossing grooves for the seating of threads therein in the usual manner.

While I have shown only two drills to produce in the button blanks a pair of eye-holes, it is obvious that the number of drills may be increased or doubled in order that the eye-holes made in the buttons may be four in number instead of two in number.

I claim as my invention:

1. In a button machine, the combination of a main frame, a vertical column surmounting said frame, a tool support fitted to said column, tools supported by said tool support for operating upon button blanks, 105 a revoluble chuck table and a revoluble turn table fitted to said column beneath said tool support, button blank holding chucks mounted in said tables, a collar extending downwardly from said turn table around 115 said column, and a lift yoke fitted to said collar whereby the collar and said tables may be raised and lowered relative to said tool support, substantially as set forth.

2. In a button machine, the combination 120 of a main frame, a vertical column surmounting said frame, a tool support fitted to said column, tools supported by said tool

support for operating upon button blanks, a revoluble chuck table and a revoluble turn table fitted to said column beneath said tool support, button blank holding chucks 5 mounted in said tables, a collar extending downwardly from said turn table around said column, a lift yoke fitted to said collar, and a rotatable cam whereby said lift yoke is elevated to move said tables toward 10 said tool support, substantially as set forth.

3. In a button machine, the combination of a main frame, a vertical column surmounting said frame, a tool support fitted to said column, tools supported by said tool 15 support for operating upon button blanks, a revoluble chuck table and a revoluble turn table fitted to said column beneath said tool support, button blank holding chucks mounted in said tables, a collar extending 20 downwardly from said turn table around said column, a lift yoke fitted to said collar, a slotted bracket attached to said main frame and in which one end of said lift yoke is fitted, an adjustment plate movably attached to said bracket and in which said lift yoke is pivoted, and a cam for engagement with the other end of said lift yoke for the operation thereof to elevate said tables toward said tool support, substantially as 30 set forth.

4. In a button machine, the combination of a main frame, a vertical column surmounting said frame, a tool support fitted to said column, tools supported by said tool 35 support, for operating upon button blanks, a revoluble chuck table and a revoluble turn table fitted to said column beneath said tool support, button blank holding chucks mounted in said tables, a collar extending 40 downwardly from said turn table around said column, a finger wheel fixed to said collar, and a rotatable trip arm having a roller

adapted to engage said finger wheel for the purpose of rotating said table, substantially as set forth.

5. In a button machine, the combination of a main frame, a vertical column surmounting said frame, a tool support fitted to said column, tools supported by said tool support for operating upon button blanks, a revoluble 50 chuck table and a revoluble turn table fitted to said column beneath said tool support, button blank holding chucks mounted in said tables, a collar extending downwardly from said turn table around said column, a lift yoke 55 loosely fitted to said collar and whereby said tables may be elevated toward said tool support, a finger wheel fixed to said collar, and means for operating said lift yoke and finger wheel comprising a driven shaft, 60 a cam fixed to said driven shaft with which said lift yoke co-operates, and a trip arm also fixed to said shaft and provided with a roller adapted to engage said finger wheel, substantially as set forth.

6. In a button machine, the combination of a chuck supporting table having an aperture therein, a chuck having a shank projecting through said aperture and secured to the table and having a tapering head 70 located above the table, a sleeve surrounding said shank and tapering interiorly at its upper end to engage the chuck head, and interiorly at its lower end around the shank of said chuck, means tending to hold the upper end of the sleeve in engagement with the chuck head, and means for retracting said sleeve at intervals to permit the chuck to open, substantially as set forth.

SIMON REINBERG.
